PRINTING MACHINE FOR PRINTING ON DIFFERENT KINDS OF COPY SHEETS

Wilhelm Ritzerfeld, Schorlemer Allee 14, Berlin-Dahlem, Germany, and Gerhard Ritzerfeld, Franzensbader Str. 21, Berlin-Grunewald, Germany

Filed Apr. 22, 1964, Ser. No. 361,912

Claims priority, application Germany, Apr. 26, 1963, R 35,035; Aug. 23, 1963, R 35,964
25 Claims. (Cl. 101—91)

The present invention relates to a printing machine for printing on different kinds of copy sheets, and more particularly to a printing machine of the type permitting the selective printing of lines or sections of a printing form mounted on a printing roller on different copy sheets which may be of different colors or shape.

Particularly in printing machines by which from one printing form, different selected text sections are printed on copy sheets, different kinds of copy sheets are used so that the color of the copy sheet will indicate the type of information contained on the copy sheet, or the particular office to which such a copy sheet has to be shown. Furthermore, since on some copy sheets the entire text of the printing form, and on other copy sheets only a few selected lines of the text are printed, copy sheets of different size and shape are advantageously used.

The order and number of each kind of copy sheets used for printing from a single printing form can be determined before the printing operation, but since such order is different for different printing jobs, automatic feeding devices according to the known art cannot be used for this purpose, since the same are incapable of handling copy sheets which are different in thickness and size. For selective printing operations of this kind, five or six or even more different copy sheet forms are used for making thirty copies. Known feeding apparatus for printing machines cannot handle such different kinds of copy sheet, and even if such feeding apparatus were known, it would have to be provided with a stack of copy sheets which are arranged in the order in which the feeding is required, and to obtain such a stack, it would be necessary to manually place the copy sheets in the desired order in the stack. Consequently, it is simpler and less expensive to have the different copy sheets supplied by the person operating the machine to standard feeding and transporting means for the copy sheets.

However, the feeding of different copy sheets in a predetermined order is a time consuming task requiring great attention of the operator, and consequently printing operations performed on different copy sheets result in a lower output of printed copies per time unit, as compared with machines in which all prints are made on the same copy sheet. On the other hand, copy sheets of different recognizable types associated with particular selections of text sections of the printing form have great advantages since they can be easily identified, and avoid the use of large copy sheets for very short texts.

It is one object of the invention to overcome the disadvantages of known copy sheet feeding devices for selective printing machines, and to provide means by which the feeding of different copy sheets is facilitated or automatically accomplished.

Another object of the invention is to provide a selective printing machine with different copy sheets at such a speed that the output of the machine corresponds to the output of a printing machine using the same kind of copy sheets for all printing operations.

Another object of the invention is to provide indicating means which indicate to the operator after each revolution of the printing roller, the kind of copy sheet which the operator has to supply to the machine.

2

Another object of the invention is to provide the printing machine with programing means which are set to a to a preselected program in the order of several series of copy sheets of different kinds and count the revolutions of the printing roller and the number of fed copy sheets to automatically control the feeding of the copy sheets in the proper order.

Another object of the invention is to provide automatic transporting and feeding means supplying copy sheets of different kinds in a preselected order to a rotary printing machine.

Another object of the invention is to automatically print during successive revolutions of a printing roller, a first kind of copy sheet with the entire text of the printing form, and other different copy sheets with selected text sections of the printing form, the selected text sections being preferably automatically changed after each revolution of the printing form.

With these objects in view, the present invention relates to a printing or duplicating machine for printing selected text sections of a printing form on different kinds of copy sheets. One embodiment of the invention comprises printing means including a rotary printing roller; programing means having a plurality of consecutive series of elements having inactive and active conditions; means actuated by the printing roller during each revolution to place the elements of the programing means successively in the active position; and a plurality of selection means respectively correlated with the different kinds of copy sheets.

The elements of each series of the programing means represent copy sheets of the same kind, and at least some of the series of elements represent different kinds of copy sheets. Each selection means is controlled by a series of elements representing copy sheets of the corresponding kind to assume the operative condition when the elements of the controlling series assume the active condition. In the operative condition of the selection means, feeding of a copy sheet of the corresponding kind is carried out by the feeding means.

This may be accomplished in different ways.

In one embodiment of the invention, each selection means includes a series of signal lamps of the same color, different series and different copy sheets being associated with lamps of different colors. When a signal lamp is placed in the operative lighted condition, it indicates by its color the kind of copy sheet which is to be supplied by the operating person to the feeding means.

Another embodiment of the invention provides transporting means, for example pairs of transporting rollers, for supplying each kind of copy sheet to the feeding means. Each transporting means is controlled by a series of elements of the programing means to start transport of the respective copy sheet when the machine is about to print a corresponding text section.

The several transporting means are disposed on different levels, and are connected by fan-shaped guide means with the feeding means by which each copy sheet is transported and fed to the printing means, and more particularly to the gap between the printing roller and a counter pressure roller.

In another modification of the transporting means, the several transporting means of the different kinds of copy sheets are mounted on a common support which is automatically raised or lowered to place the transporting means associated with the required kind of copy sheet at the level of the feeding means so that the correct copy sheet is fed to the printing means.

According to one arrangement of the present invention, the revolutions of the printing roller are counted by electric counting means producing counting impulses

which are supplied to a matrix whose outputs are connected to the several transporting means which are associated with different kinds of copy sheets.

The outputs of the matrix are advantageously connected to means by which different text sections are selected for printing during successive revolutions of the printing roller. In this manner, the sequence of selected text sections printed during successive revolutions of the printing roller, is determined between revolutions of the printing roller.

The outputs of the matrix are preferably provided with branch lines for controlling the printing means in such a manner that the time of cooperation between the printing roller and the counterpressure roller is influenced.

In a preferred embodiment of the invention, the counting impulses control electromagnetic means which either directly control the cooperation between the printing roller and counterpressure roller, or influence the same through axially, and preferably also circumferentially adjustable control cams by which the movements of the counterpressure roller to and from a printing position is derived.

The counting impulses of the counter means by which the revolutions of the printing roller are counted, may be successively supplied to a program storing means which is formed of several, preferably electric counter means, connected in series, which determine, by means of pre-selecting devices, the transmission of impulses to the next counter means in a selective manner, and which operate the counting devices of the program storing means until the same operate the corresponding transporting means for the copy sheets, until the electric counting means return to the initial position of rest.

For the selection and operation of the specific means for supplying copy sheets of different kinds, and for at the same time controlling the moment, and time of cooperation between printing roller and counterpressure roller, it is preferred to provide two parallel counting devices with associated, independently operating program storing devices.

The transporting means of the several kinds of copy sheets are preferably placed in a transporting condition by electromagnetic coupling means connecting a selected transporting means with continuously operating drive means, and the electromagnetic coupling means being selectively energized by the counting impulses of the counting devices in cooperation with the program storing devices.

In the preferred embodiment of the invention, photoelectric sensing means are provided for sensing a selected copy sheet transported by the transporting means, so that the printing machine starts only when a copy sheet is supplied to the main feeding means.

In another embodiment of the invention, the transporting means of the several kinds of copy sheets are arranged at different levels on a shiftable support, which is operated to place the transporting means of the required kind of copy sheet at the level of the main feeding means. Counting impulses of the counting means control the shifting of the support to a correct position in which the required kind of copy sheet is supplied to the main feeding means of the machine.

The impulses of the counting device control the number of operations of each copy sheet supplying transporting means before all the copy sheets of the several transporting devices have traveled the distance to the printing roller, which is substantially the same for all transporting means.

In another modification of the invention, the moment, and the time period of cooperation between the printing roller and the counterpressure roller is regulated in accordance with the position of the support of the several transporting means.

The cams by which the selection of text sections of the printing form is controlled, are rendered operative by electromagnetic means in accordance with the program selection. It is possible to control and operate the support of the several transporting means by counting impulses in such a manner that certain transporting means are skipped and the respective copy sheets are not used.

The novel features which are considered as characteristic for the invention are set forth in particular in the appended claims. The invention itself, however, both as to its construction and its method of operation, together with additional objects and advantages thereof, will be best understood from the following description of specific embodiments when read in connection with the accompanying drawings, in which:

FIG. 1 is a fragmentary schematic side view, partially in section, illustrating one embodiment of the invention, a side wall of the frame being omitted for the sake of clarity;

FIG. 2 is a sectional view taken on line II-II in FIG. 1;

FIG. 3 is a sectional view taken on line III-III in FIG. 1;

FIG. 4 is a diagrammatic view illustrating a printing form, and the different kinds of copy sheets selected in accordance with a program;

FIG. 5 is a side view, partially in section, illustrating another embodiment of the invention, a side wall of the frame being omitted for the sake of clarity;

FIG. 6 is a fragmentary side view illustrating on an enlarged scale a portion of FIG. 5;

FIG. 7 is a fragmentary sectional view taken on line VII-VII in FIG. 5;

FIG. 8 is a fragmentary sectional view taken on line VIII-VIII in FIG. 5, and being developed for the sake of clarity;

FIG. 9 is a diagram illustrating the electric circuit and the counting devices of the embodiment of FIGS. 5 to 8;

FIG. 10 is a diagram illustrating the electric circuit of sensing means used in the embodiment of FIGS. 5 to 9;

FIG. 11 is a side view, partially in section, illustrating a third embodiment of the invention, one side wall of the frame being omitted for the sake of clarity;

FIG. 12 is a fragmentary side view illustrating on an enlarged scale a detail of the embodiment of FIG. 11;

FIG. 13 is a fragmentary sectional view taken on line XIII-XIII in FIG. 11;

FIG. 14 is a diagram illustrating the electric circuit of the embodiment of FIGS. 10 to 13; and

FIG. 15 is a partial fragmentary side view illustrating a detail of the embodiment of FIGS. 11 to 14, and partly an electric circuit used in this embodiment.

Referring now to the drawings, and particularly to the embodiment illustrated in FIGS. 1 to 3, a printing roller 3 is connected by a one revolution clutch, not shown, with continuously operating drive means including meshing gears 302, 303 and 304, and a pulley 305 which is driven from a motor, not shown, in the usual manner. Gear 304 and a chain sprocket 307 are fixed to the drive shaft 306 which is rotated by pulley 305. A chain 308 connects sprockets 307 with another sprocket on a shaft 327 by which an electromagnetic coupling 309 is driven, as best seen on the right side of FIG. 2.

A gear 311 is secured to the shaft 310 of the printing roller 3 and meshes with a gear 312 driving a gear 313 on a cam shaft 14. Consequently, cam shaft 314, with cam means 315, 315a, 316 rotates in synchronism with the printing roller 3.

FIG. 2 illustrates only one cam 15 which has a cam lug 316, but it will be understood that a number of adjustable cams may be mounted for turning and axial movement on shaft 314 to select head section and other line sections of the printing form, as is known to those

skilled in the art. The cam selecting arrangement which will be described with reference to FIG. 8, may also be used in the embodiment of FIGS. 1 to 3. Cams on cam shaft 314 cooperate with a follower roller 317 mounted on a lever of a lever system by which the counterpressure roller 13 is moved between a printing position cooperating with a printing form 346 on printing roller 3, and a retracted inoperative position. Spring means, not shown urge counterpressure roller 13 to the retracted position shown in FIG. 1. When cam lug 316 engages follower roller 317, counterpressure roller 13 is moved to the printing position so that a copy sheet supplied by feeding rollers 341, 342 to the gap between the printing roller and the counterpressure roller is imprinted by the corresponding text section of printing form 346. Since the copy sheet is transported by the cooperation between the printing roller and the counterpressure roller, it stops when the counterpressure roller is retracted, so that several selected text sections, or a head section and a text section, are printed in adjacent positions on the copy sheet, as is known to those skilled in the art.

Cam 315 is automatically shifted one step after each revolution of the printing roller so that successive text lines of the printing form are printed during successive revolutions of the printing roller, if desired. Cam 315, a switch control arm 324, and a gear 325 are secured by bolts to a housing member 323 of a spring-loaded stepping mechanism which includes a ratchet wheel 321, a shifting pawl 320, a locking pawl 319, and a spiral spring 322 which are normally locked by pawl 319, but which will perform a step when pawl 320 is displaced by an actuating member, not shown in FIG. 1, but exactly corresponding to the actuating members 42a, 42b, 42c shown in FIG. 5. When the stepping mechanism is operated by an actuating member in operative position, which takes place at the end of a revolution of the printing roller, the stepping mechanism is shifted one step, and the cam lug 316 of cam 315 is displaced a corresponding angular step so that during the following operation, cam follower roller 317 is engaged later during the revolution of the printing roller, so that the counterpressure roller is moved to the printing position when the next following line section of the printing form passes through the printing plane, as compared with the preceding revolution of the printing roller.

Gear 325 meshes with a gear 326 which meshes with a gear 328 on shaft 327. Shaft 327 is rotated from drive shaft 306 and drive 307, 308, 307a when electromagnetic coupling means 309 is energized and the two coupling parts 309a and 309b are in the engaged coupling position. When shaft 327 is rotated in this manner, spring 322 is wound up by turning the housing 323 to which one end of the spring is secured.

As best seen in FIG. 3, shaft 327 is connected by an electromagnetic coupling means 329 including two coupling parts 329a and 329b to a sprocket 330 driving through a chain 331 another sprocket 351 and a contact arm 352 whose resilient contact 343 passes over a series of contacts 344 arranged along a circle on a contact plate 343, as best seen in FIGS. 1 and 3. Contact plate 334 is fixed to the frame of the machine, and carries pawls 336 and 337, and a control lever 339 which is rockable about a pivot 338.

Contacts 344 of contact plates 334 are respectively connected to signal lamps 335a, 335b, and 335c which have different colors, for example, red, green and white. A series of successive contact elements 344 is connected to each signal lamp, the number of contact elements 344 of the same series connected to the same lamp being selected in accordance with a program.

The lamps 335a, 335b, 335c are respectively correlated with different kinds of copy sheets, so that when, for example, a lamp of a specific color lights up, the operator of the machine will select a kind of copy sheet

associated with the respective color of the signal lamp, and supply it to the feeding means 341, 342.

Pawl 337 and 336 are spring-loaded, and cooperate with a ratchet wheel 333 which is secured to contact arm 332. Normally, pawl 337 engages the ratchet wheel 333 and prevents the same from turning under the action of a spring 348. When coupling means 329a, 329b is energized and in coupling condition, the contact arm 332 with ratchet wheel 333 is rotated against the action of spring 348 so that the same is tensioned to provide a force for turning the ratchet wheel when the coupling means 329 is again deenergized, which is the normal condition of coupling means 329.

As is shown in FIG. 1, signal lamp 335a is connected to a series of three contact elements 344 which are the first to be engaged by contact 343 of contact arm 332 during rotation of printing roller 3 in a direction of the arrow E. The second signal lamp 335b is connected to only one contact element 344, while the third signal lamp 335c is connected to a series of contact elements 344 which includes all remaining contact elements. Since each signal lamp is correlated with a particular kind of copy sheet which may be different in color or size, the corresponding series of contact elements 344 is associated with the same kind of copy sheets, but different series of contact elements are associated with different kinds of copy sheets. It is evident that more or fewer contact elements may be connected to each signal lamp in accordance with a program, and consequently the respective connectors and contact elements constitute programming means. A contact element 344 not engaged by contact 343 of contact arm 332 is in an inactive position, but when contact 343 engages a contact element 344, it is in an active condition since the corresponding signal lamp is connected into a circuit, and lights up. The circuit includes a slide ring 335d connected to contact 343, and a slide contact 335e sliding on the slide ring and being connected to the source of voltage whose other terminal is connected to the signal lamps.

40 A switch 350 is operated by control arm 324 on shaft 314, and is connected in series with a manually operated switch 349 and the electromagnetic coupling means 309 and 329, as schematically illustrated in FIG. 1.

The embodiment illustrated in FIGS. 1 to 3 operates as follows:

45 The program is selected by connecting each of the signal lamps to a corresponding series of contact elements 344, the second series consisting of only a single contact element, and the first series consisting of four contact elements so that contact 343 engages the first contact element 344, closing the circuit of the red signal lamp 335a so that the same is lighted.

The machine is operated as follows:

50 Since the red signal lamp 335a is lighted, the operating person places a red copy sheet 345 between the feeding rollers 341, 342, and when rotation of printing roller 3 is started by engaging the one revolution coupling, not shown, of the drive means, printing roller 3 rotates in the direction of the arrow E out of the initial position shown in FIG. 1.

55 Since cam shaft 314 rotates in synchronism with the printing roller, being driven by the gear train 311, 312, 313, cam shaft 314 turns in the direction of the arrow F with the cam 315 thereon. Pawl 319, secured to gear 313, is in the position engaging ratchet wheel 321 and consequently the same is turned together with cam 315 and switch control arm 324.

60 65 70 75 When the desired and selected section of the printing form passes the printing plane G-H, cam lug 316 of cam 315 engages cam follower roller 317 so that counterpressure roller 13 is moved to its printing position whereby the respective text section of printing form 346 is printed on a copy sheet 345 located in the printing plane G-H between the printing roller and the counterpressure roller.

Shortly before printing roller 3 has completed its first revolution, a roller 347, see FIG. 1 and FIG. 3, secured to gear 311 engages control lever 339 and turns the same about pivot 338 so that the free end of control lever 339 engages shifting pawl 336 and releases ratchet wheel 333 of the stepping mechanism on shaft 310 to turn one step under the action of spring 348 until ratchet wheel 333 is again stopped by pawl 337 falling into the following notch of the ratchet wheel. Consequently, contact arm 332 with contact 343 is shifted one step to a position in which contact 343 engages the next following contact element 344, rendering the same active so that the red signal lamp 335a is again lighted, although the first contact element 344 was rendered inactive by the contact arm. The red signal lamp indicates to the operator that a red copy sheet is again required in accordance with the program, and the operator will supply such a copy sheet to the feeding means 341, 342.

In this fashion, the signal lamp acts as a selection means which causes the operator to carry out a corresponding selection of the kind of copy sheet associated with the respective signal lamp.

The same operations are repeated after each revolution of the printing roller, and since four contact elements 344 are connected to signal lamp 335a, four red copy sheets are printed. The actuating means, not shown, by which pawl 320 can be operated, are held, for example, in an inoperative position, so that pawl 319 establishes a coupling connection with ratchet 321, and cam 315 remains in the same position during the printing of the four consecutive red copy sheets whereby the same text appears on the same.

When contact arm 332 moves from the fourth contact to the fifth contact element 344, the green signal lamp 335b is connected into the circuit, and lights up, indicating to the operator that a green copy sheet has to be supplied to feeding means 341 and 342. Before the rotation of the printing roller is started, another cam 315a, not shown in FIG. 4 may be placed in a position for operating cam follower roller 317 and counterpressure roller 13, so that another text section of printing form 346 can be printed. By selecting suitable cams, it is also possible to print the entire text on the first series of copy sheets, and to print a particular text section by cam 315a on a green copy sheet.

When contact arm 332 moves to a position in which contact 343 engages a contact element 344 connected to the white signal lamp 335c, an actuating means corresponding to the actuating means 42a in FIG. 5 is placed in an operative position engaging shifting pawl 320 so that during each revolution of printing roller 3 and cam shaft 314, ratchet wheel 321 is permitted to make one step under the action of spiral spring 323. Consequently, during successive revolutions of printing roller 3, a different text section will be printed on consecutive white copy sheets supplied by the operator to the feeding means 341, 342, since during each revolution, the displaced cam lug 316 will engage cam follower roller 317 later in relation to the rotation of printing roller 3 with printing form 346 so that successive text sections pass through the printing plane G-H during each revolution at the moment in which cam lug 316 displaces cam follower 317 and thereby counterpressure roller 13.

As long as signal lamp 335c is lighted, the operator will supply a white copy sheet to the feeding means 341, 342 so that the white copy sheet will be imprinted with single lines, but each copy sheet will receive a different selected single line of the printing form.

Since the length of the printed text is the same for all white copy sheets, they may be made shorter than, for example, red copy sheets receiving the entire text of the printing form.

When several actuating means are provided, as shown in FIG. 5, cam 315, 316 will be displaced two or more angular steps, so that instead of consecutive lines of the

text, text sections spaced one or two lines will be printed on the respective copy sheets.

When all copy sheets are printed in accordance with the preselected program, contact arm 332 moves off the last contact element 344 connected to the white signal lamp 335c so that the same becomes inoperative and is extinguished. It is not necessary to connect all remaining contacts 344 to the white signal lamp, since the smaller number of copy sheets than contact elements 344 may be required. In any event, the printing machine is returned to its initial condition by operation of switch 349 which closes a circuit to the electromagnetic coupling means 309 and 329. The drive part of coupling 309 is driven by chain 308 from drive shaft 306, and when the coupling is energized, the driven part 309b is driven by shaft 327 so that gear 328 drives gear 325 through gear 326 whereby gear 325 and control arm 324 are rotated in a direction of the arrow F until control arm 324 engages switch 350 and opens the same so that the electromagnetic coupling 309 and the electromagnetic coupling 329 are deenergized. As long as shaft 327 rotated, and coupling means 329 was energized at the same time as coupling means 309, coupling part 329a is driven by shaft 327 and drives coupling part 329b so that the chain drive 330, 331, 351 rotates contact arm 332 until the same abuts a stop 352 on contact plate 334, as shown in FIGS. 1 and 3. Contact arm 332 is stopped at the same moment in which control arm 324 opens switch 350 and de-energizes the two electromagnetic coupling means 309 and 329. All movable parts of the machine are now in the initial position so that a new printing form may be mounted on the printing roller, and a new program selected by connecting different series of contact elements 344 to the three signal lamps. Evidently, a greater number of different distinguishable signal lamps, or other indicating means, may be provided if the prints are to be made on a greater number of different copy sheets. In any event, each indicating means, such as a signal lamp, correlated with a particular kind of copy sheets, indicates the necessary selection to the operator so that he may supply corresponding copy sheets to the feeding means.

While in the embodiment of FIGS. 1 to 3, the selection is indicated to the operator, the embodiments of FIGS. 4 to 10, and FIGS. 11 to 15 are provided with selection means which effect automatic selection of the particular desired kind of copy sheet, and transport of the respective copy sheets to the feeding means.

FIG. 4 shows a printing form whose first seven lines or sections contain a text to be printed. The first two lines are designated Pr. 1 and constitute a program, such as a head section, which will have to be repeated on all copy sheets. The following lines T3 to T7 may be referred to as "transported" lines since they do not necessarily appear on all copy sheets, selected lines being printed on some copy sheets, and successive lines being printed on successive copy sheets during successive revolutions of the printing roller, as required.

As schematically indicated by FIG. 4, the printing operations are to be carried out on five different kinds of copy sheets 2, 4, 5, 6, and 7, which are respectively white, yellow, red, pink and green. Copy sheets of different colors are to receive different selections of the full text of the printing form 1. In accordance with the program schematically indicated in FIG. 4, two white copy sheets are to receive imprints of all seven lines, that is of the entire text of the printing form during the first two revolutions of the printing roller. Three prints of the first three lines are to be made on three yellow copy sheets 4 and on three pink copy sheets 4 in the following six revolutions of the printing roller. Thereupon, lines 1 and 2 and line 4 are to be printed on one yellow copy sheet and on two red copy sheets. By printing the same text on copy sheets of different colors, the respective copy

sheets may be easily identified and directed to different offices requiring the same information.

The following printing operations according to the program will result in printing of the text line T5 on two yellow copy sheets 4, two pink copy sheets 6 and one copy sheet 7, then the printing of the text line T6 on three yellow copy sheets, and finally the printing of the text line T7 on one red copy sheet 5, two pink copy sheets 6, and one green copy sheet 7.

The printing machine which is provided with the apparatus of the invention is of a well known construction, and shown to be a rotary duplicating machine including a printing roller 3 having a holding means 11 for clamping a printing form 1 to its periphery and rotating with a shaft 8 driven by drive means, not shown. A counter-pressure roller 13 cooperates with printing roller 3. Copy sheets are transported and fed by a pair of feeding rollers 48, 49 into the gap between the printing roller and the counterpressure roller and are imprinted with selected text section when the counterpressure roller is moved to a printing position in close proximity to the periphery of printing roller 3.

Counterpressure roller 13 is shifted between an inoperative position and the printing position by an intermediate lever system including levers 32 mounted on a shaft means 12, toggle levers 33, 34 loaded by spring 160 and being adjustable by an eccentric member supporting lever 34, a lever 31 engaging a pin means on a lever 23 which is mounted on a shaft 26 in the frame of the machine and has a cam follower roller 28 cooperating with cam means including a cam 15 having a cam lug associated with the head section of the text, cams 16a and 16b by which the head section can be extended two lines. Cam 15 is fixedly connected by a flange member 19 to shaft 14. Another cam 17 is mounted on shaft 14 and has such a cam shape as to permit the printing of the entire text of the printing form. The cam group 16a, 16b, 17 can be shifted in axial direction along shaft 14 to place cams 16a and 16b in engagement with cam follower roller 28 on a cam follower lever 24, while in the position illustrated in FIG. 8, cam 17 cooperates with a cam follower roller 27 on a cam follower lever 23 which is also secured to shaft 26. A third cam follower lever 25 secured to shaft 26 has a cam follower roller 29 cooperating with cams 19a, 19b and 19c when the same are shifted in axial direction on shaft 14. These cams are associated with text sections and have different length, for example corresponding to one, two or three lines so that depending on the position of the cam group 19a, 19b, 19c, one, or two, or three lines can be printed. Cams 19a, 19b, 19c are mounted on the housing part of a spring-loaded stepping mechanism including shifting pawls 37, 36, a ratchet wheel 38, and a spiral spring 35 which upon operation of shifting pawl 37 by any of the actuating members 42a, 42b, 42c will permit ratchet wheel 38 to make a single step, or two steps, or three steps together with the cam group 19a, 19b, 19c, and such steps will be made after each revolution of the printing roller since shaft 14 rotates in synchronism with the printing roller 3 with which it is connected by a gear train 20, 21, 22.

According to the effective length of the cam projections of the cams in operative positions engaging cam follower rollers, the cam follower levers 23, or 24, or 25 are operated so that the intermediate lever 30 and the toggle lever system 31 to 34 transmit motion to counterpressure roller 13 which is moved to its printing position at the moment in which a selected section of the printing form, corresponding to the cam lug of the respective cam, passes through the printing plane A-B. The actuating means 42a, 42b, 42c by which an automatic step, or steps, of the cams 19a, 19b, 19c is effected after each revolution, are provided with rollers which engage shifting lever 37, and operated by electromagnetic means 43a, 43b, 43c

which are controlled by a matrix 44, which will be described hereinafter in greater detail with reference to FIG. 9.

The shifting of cams 19a, 19b, 19c in axial direction to positions cooperating with cam follower means 25, 29 is accomplished by electromagnetic means 134, 135, 136 which are automatically operated under control of the matrix 44, but it is also possible to manually shift the cams by operation of the rod 137 on which the armatures of electromagnetic means 134, 135, 136 act. Rod 137 is biased by spring 147 to move to the left as viewed in FIGS. 5 and 8, and acts on a lever 139 connected by a pivot 140 to another lever 141 which is connected by a pivot 142 to the arm of a sleeve 143 having a slot 144 of helical shape. Consequently shifting of a rod 137 by the electromagnetic means, or the manual operation, will cause turning movement of sleeve 143, and due to the helical shape of slot 144, a pin 146 and secured to a member 145 will move in axial direction so that the entire cam group 19a, 19b, 19c will be shifted with member 145 in axial direction to place cams 19c, 19b, 19a successively in a position cooperating with cam follower roller 29.

Cams 17, 16a, 16b are shifted in a similar manner by a member 158 engaging with a pair of forked arms the flange member to which cams 17, 16b, 16a are secured by a bolt 18. A pin 159 on member 158 projects into a helical slot in a sleeve 157 having an arm connected by pivot means 154 to a lever 153 pivotally connected at 152 to another lever 151 which is articulated to a rod 148 cooperating with three electromagnetic means including electromagnetic means 47 associated with cam 17 by which the entire text can be printed, and electromagnet means 45 and 46 associated with cams 16a and 16b by which the text of the head section can be extended.

This arrangement is not an object of the invention and disclosed in our copending application Serial No. 351,668 entitled "Cam Controlled Printing Machine," the basic features of the cam arrangement for controlling the counterpressure roller being also disclosed in our U.S. Patent 2,868,116.

Electromagnetic means 45, 46 and 47 can be energized by manually operated switches 131, 132, 133, and a corresponding set of manually operated switches, not shown, 45 is provided for operating electromagnetic means 134, 135, 136. Each of the electromagnetic means has an armature projecting into a corresponding cutout of the respective rod 148 or 137 so that each electromagnetic means can perform its function independently of the other electromagnetic means.

In the cam position shown in FIG. 8, the entire text of the printing form will be printed, since cam follower roller is in engagement with cam 17. Cam follower roller 28 will also be operated by cam 15 associated with the head section.

When the cam group 16a, 16b, 17 is shifted in axial direction, cam 17 will be no longer engaged by cam follower 27, while cam 15 will remain effective to print the head section. Such head section can be extended by placing cams 16a or cam 16a and 16b under cam follower roller 28.

If it is desired to print one line of the text in addition to the head, cam 19a must be placed in a position cooperating with cam follower 29, and when, for example, 65 the actuating means 42a is shifted to an operative actuating position engaging the shifting pawl 37, cam 19a will be shifted one step in circumferential direction after each revolution of the printing roller so that successive lines of the text section will be printed in addition to the head section.

For each of the several different kinds of copy sheets, a table 50, 51, 52, 53, 54 is provided on which stacks of the respective copy sheets are placed. As explained with reference to FIG. 4, the copy sheets are of different color,

and as best seen in FIGS. 5 and 6, the copy sheets 2, 4, 5, 6, 7 are of different length, copy sheet 2 being designed to receive an imprint of the entire text, while copy sheets 5, for example, will receive only a single line of the text.

The copy sheets are transported by transporting means including rollers 55, 56, 57, 58 and 59, which are respectively driven by electromagnetic couplings 60a, 60b, 60c, 60d, and 60e when the same are energized, and which are not driven when the couplings are deenergized and disengaged. The couplings are driven from a drive shaft 61 through a chain drive including chain sprockets 62, 63, 64, 65, 66, 67, 68 and 69. The several support tables for the stacks of copy sheets are located at different horizontal levels, and each support table is correlated with fan-shaped guide means 77, 78, 79, 80, 81, which have outlets for copy sheets located in the region of moistening means 76 and feeding rollers 48 and 49.

Intermediate guide means 76 to 81 and the several transporting rollers 55 to 59, fan-shaped conveyor means are arranged which include the conveyors 70, 71, 72, 73 and 74 each of which includes two conveyor belts guided about conveyor rollers and having adjacent portions between which copy sheets are transported toward the guide means 77 to 81. The conveyor rollers are mounted on shafts 75 which are driven by pulley and belt drive 130, as best seen in FIG. 7. Each transporting means, for example transporting rollers 55 and conveyor belt 70 will transport the corresponding copy sheet toward the guide means, for example 77, when the respective coupling 60a is energized, so that the feeding rollers 48, 49 will transport a thus selected copy sheet to the printing plane between printing roller 3 and counterpressure roller 13.

When a copy sheet arrives in the region of the feeding means 48, 49, its presence is sensed by a photoelectric sensing means 82 including a source of light 83 projecting a beam onto the feeding roller 49, and a photocell 84 which will create an impulse when sensing the leading edge of a selected copy sheet transported by the transporting means into the region of the feeding means.

FIG. 10 illustrates a circuit of the photoelectric sensing means which includes an amplifier 99 and an electromagnetic means 100 responding to impulses produced by the photoelectric sensing means.

FIG. 9 illustrates the circuit of the apparatus. A key 85 controls two switches 86 and 89. Switch 86 connects the electromagnetic means 43a, 43b, 43c through an amplifier 88 with the gate 87 of a matrix 44. Electromagnetic means 43a, 43b and 43c control the actuating means 42a, 42b, 42c by which the stepping mechanism of cams 19a, 19b, 19c is actuated. Switches, not shown, permit the selection of one, two or three of the electromagnetic means 43a, 43b and 43c for energization and control of the corresponding actuating member.

The second switch 89 connects a counter 91 and matrix 44 to a voltage source. At the same time electromagnetic means 45 is energized through an amplifier 90, electromagnetic means 45 being shown in FIG. 8 and FIG. 5 to control rod 148 by which cam group 16a, 16b, 17 is shifted in axial direction.

The matrix 44 constitutes a programming means and has a number of outputs connected to switches operated by a manually operated rod 104. Diodes or other valves are provided in lines 8, 11, 16 and 19 which are connected to gate 87 in accordance with the selected program of printing on different kinds of copy sheets.

Referring again to FIG. 6, it will be seen that shaft 8 of the printing roller carries a cam 101 for operating two switches 97 and 102. Switch 102 is connected to the counters 111 and 91, and switch 98, when closed, connects the electromagnetic coupling means 60a, 60b, 60c, 60d and 60e of the transporting means for the copy sheets to one terminal of the source of voltage, or to

10

mass. The electromagnetic coupling means are respectively connected to amplifiers 96, 106, 127, 119 and 123 which are respectively connected to gates 92, 103, 129, 121 and 125, each of which is connected to one output of the matrix 44 by the switch means 104.

Gates 92, 103, 129, 121 and 125 are respectively connected to a storing counter 113 which is connected to counter 111. Preselecting devices 112a, 112b and 112c are operated by switches 93, 94, 95 to set the storing counter 113. Switch 108 which connects counter 111 to the source of voltage, also connects an electromagnetic program means 110 into the circuit.

The apparatus is operated as follows:

Switch 85, 89, 86 is manually closed so that electromagnetic means 43a is energized and actuating means 42a is placed in an actuating position in which it will be engaged by the rotating shifting pawl 37 during a revolution of the printing roller and of cams 19a, 19b, 19c. Electromagnetic means 45 is energized and shifts rod 148; see FIG. 8, so that cam 15 of the head section is operative. At the same time, the matrix 44 is energized and placed in its initial position so that on the first of the twenty-three illustrated output lines of the matrix, a potential is created which acts through gate 92 and amplifier 96 to energize electromagnetic means 47, and to connect electromagnetic coupling means 60a to voltage. Electromagnetic means 47 also controls rod 148 so that sleeve 157 is turned, and cam group 17, 16a, 16b shifted in axial direction, as best seen in FIG. 8 resulting in a position in which the entire text will be printed under control of cam 17. Transporting rollers 55 are not yet driven, since electromagnetic coupling means 60a is not energized since the circuit is still interrupted by the cam operated switch 97 and by the manually operated switch 98.

Switch 93 is a start switch by which the printing operation is started. Electromagnetic coupling means 60a is energized and connects transporting rollers 55 to the chain drive explained with reference to FIG. 6, so that a white copy sheet 2 is transported to the conveyor means 70 and transported by the same to a position in which the copy sheet passes over guide means 77 and is moistened by moistening means 76 before being engaged by the feeding rollers 48, 49. At the moment in which the leading edge of copy sheet 2 engages the feeding rollers, the amount of light reflected into photocell 84 is changed so that an impulse is created in the photocell which energizes through amplifier 99 the electromagnetic means 100, see FIG. 10. Electromagnetic means 100 controls the circuit of the one revolution clutch through which the printing roller 3 is driven from continuously rotating drive means, not shown, so that upon sensing of a copy sheet in the region of the feeding means 48, 49, the printing roller is started to perform a revolution.

Printing roller 3 with printing form 1 starts to rotate while feeding rollers 48, 49 supply the copy sheet to the printing plane A-B between printing roller 3 and counter-pressure roller 13. Due to the fact that electromagnetic means 47 is energized, cam 17 is operative and the entire text of the printing form is printed on the first copy sheet 2.

In the meantime, cam 101 operates counter switch 102 so that the counter 91 is shifted one unit.

Shortly before printing roller 3 arrives in its initial position, cam 101 actuates switch 97 so that the circuit of the electromagnetic coupling means 60a is again closed, which was opened upon release of switch 98 by the operator. Consequently, a white copy sheet 2 is automatically transported to the feeding means 48, 49 during the following second revolution of the printing roller. At the output No. 2 of matrix 44, gate 92 is again excited since the first two output lines of the matrix are connected to gate 92, corresponding to the predetermined program according to which two copies of the entire printing form are to be made on two white copy sheets, as ex-

plained with reference to FIG. 4. Electromagnetic coupling means 60a and electromagnetic means 47 are again energized, and cam 17 is again operative to cause printing of the entire text of the printing form. When sensing means 82 senses the second white copy sheet in the region of the feeding means, the second revolution of the printing roller 3 is started by electromagnetic means 100, and the second white copy sheet is imprinted with the entire text. The cam lug 101 operates switch 102 so that counter 91 adds a unit and renders output 3 of matrix 44 operative. In accordance with the preselected program, output 3 is connected through output gate 103 so that amplifier 106 is energized, and electromagnetic coupling 60b of the transporting rollers 56 of the yellow copy sheets 4 is connected to voltage. Shortly before printing roller 3 arrives in its initial position, cam lug 101 operates switch 97 so that the circuit of the electromagnetic coupling 60b is closed, and transporting roller 56 transports the uppermost yellow copy sheet 4 to the conveyor means 21 which supply the copy sheet along guide means 78 to the feeding means 48, 49.

Sensing means 82 sense the presence of the selected copy sheet, and cause start of the next following revolution of printing roller 3. The following revolutions of printing roller are automatically carried out in succession, with cam operated switch 102 causing successive placing of the output lines of the matrix in an active condition by operating counter 91. Three yellow copy sheets are selected by the selection means including electromagnetic coupling 60b and transporting rollers 56 since the three output elements are connected to gate 103. Another three output elements of the matrix are connected to gate 121 which connects the electromagnetic coupling 60d into the circuit so that during the sixth, seventh and eighth revolution of the printing roller, three pink copy sheets 6 are selected and imprinted. During the printing of the yellow and pink copy sheets, electromagnetic means 47 is not energized so that cam 17 is rendered inoperative and not the entire text is printed, but only the head section of the text since cam 15 is rendered operative by electromagnetic means 45, and also a selected line section since cam 19a is rendered operative by one of the electromagnetic means 134, 135, 136, or by manual operation of rod 137. Consequently, the three yellow and the three pink copy sheets are imprinted with a head section Pr 1 comprising two lines, and with a third line T3 of the printing form.

When after repeated energization of counter 91, the eighth output element of the matrix 44 is placed in the active condition, and a potential appears on the eighth output line, gate 87 supplies an impulse through switch 87 to amplifier 88 which energizes electromagnetic means 43a so that actuating means 42a, see FIG. 5 is shifted to an actuating position located in the circular path of shifting pawl 37 so that the same is operated and causes ratchet wheel 38 to turn one step with the housing to which spring 35 is secured so that cam 19a is turned one step whereupon the locking pawl 36 stops further rotation of the ratchet wheel. Consequently, the position of the cam lug of cam 19a has been changed so that cam 19a is effective to operate cam follower means 29, 25, and to shift counterpressure roller 13 to the printing position when the fourth line of the printing form passes through the printing plane during the following revolution of the printing roller.

In accordance with the program explained with reference to FIG. 4, the first two and the fourth line of the printing form are printed on one yellow sheet and on two red copy sheets and consequently the ninth output element of the matrix 44 is connected to gate 103 and to the electromagnetic coupling 60b of the transporting roller for the yellow copy sheets 2, while the tenth and eleventh output line elements are connected through gate 129 and amplifier 127 to the electromagnetic coupling 60c by which the transporting rollers 57 of the red copy

sheets 5 are driven. The eleventh output element is connected to gate 87 so that electromagnetic means 43a is again energized to operate the stepping mechanism whereby cam 19a is turned one step to cause printing of the fifth line of the printing form on two yellow copy sheets 4, two pink copy sheets 6, and one green copy sheet 7, the sixteenth output element of the matrix being connected to output gate 125 and through amplifier 123 to electromagnetic coupling 60e controlling the transporting rollers 59 by which the green copy sheets 7 are supplied to the conveyor means 74 which further transport the copy sheet over guide means 81 to the feeding means 48, 49 where the copy sheet is sensed to start the next following revolution of the printing roller by electromagnetic means 100 which start the one revolution clutch of the printing roller in a manner which is known, and therefore not illustrated.

The operations are automatically continued in accordance with the program since during each revolution a counting impulse is given by cam operated switch 102 to counter 91 which shifts the matrix 44 so that the several series of output elements which are respectively associated with different kinds of copy sheets are successively placed in the active condition in which an impulse is supplied to 20 the respective associated transporting means which supply the corresponding copy sheet to the feeding means. The stepping mechanism is actuated after each revolution, so that successive lines of the printing form are printed on three yellow copy sheets, and then on one red 25 copy sheet 5, two pink copy sheets 6, and one green copy sheet 7, as indicated by the program of FIG. 4, and in accordance with the connections of the output line elements of the matrix to the output gates 103, 129, 121, and 125. The diode valves 107d decouple the output 30 gates when required due to the shifting from one kind of copy sheet to the other copy sheet, since copy sheets of the same kind, for example pink or yellow copy sheets are supplied by the respective transporting means under the control of several energized gates. For example, when 35 gate 103 receives an impulse when the fifth output element of the matrix 44 is active, such impulse is not supplied to gate 87 due to the provision of the diode valve 107 in the nineteenth output line.

Starting from output line element 9 of the matrix, the 40 first two lines, and different single lines of the text are printed on the respective selected copy sheets. When all copy sheets are imprinted in accordance with the program, and no copy sheet is supplied to the feeding means 48, 49, the sensing means 82 is not energized 45 so that electromagnetic means 100 is not energized and consequently no further revolution of the printing roller 3 is started. The stopped machine may be provided with a different printing form, and a different program 50 may be set in matrix 44 by connecting other output elements in accordance with the program to output gates 92, 103, 129, 121, 125 and to output gate 87.

In the preceding description of printing operations according to one program, it was assumed that electromagnetic means 43a was disconnected from the other electromagnetic means 43b and 43c so that the line selecting cam 19a performed only a single step after each revolution. If two electromagnetic means 43 and 43b are connected to switch 86, the respective cam 19a will turn two steps so that every second line will be printed, and simultaneous energization of the third electromagnetic means 43c will cause jumping of the respective cam through three steps. In this event, rod 137 is shifted to render either cam 19b, or cam 19c operative, which cams have cam lugs corresponding to two lines, and three lines 65 of the printing form so that after each control signal from gate 87, two, or three successive different lines are printed during successive series of revolutions of the printing roller.

The apparatus can also be set to a different program 70 according to which it is not desired to print different

selected lines or groups of selected lines during successive series of revolutions of the printing roller. Switch 108, which was opened during the above explained operation of the apparatus, is closed, and switch 85, 89, 86 remains open. When the apparatus is set in this manner, a certain number of selected lines is printed on different copy sheets. Closing of switch 108 connects amplifier 109 and electromagnetic means 110, as well as counter 111 into the circuit. At the same time, switch 93 of preselecting means 112a is closed to set the storing counter 113 to a selected number. The number is preferably indicated by indicating means which also show the number of printed copy sheets. A program is assumed according to which four imprints are to be made on white copy sheets 2, seven imprints are to be made on yellow copy sheets 4, five imprints are made on red copy sheets 5, three imprints are made on pink copy sheets 6, and four imprints are made on green copy sheets 7. Storing counter 113 is correspondingly set so that its units which are respectively connected to gates 92, 103, 129, 121 and 125 store the respective number of the respective kind of copy sheet in accordance with the program. Switches 94 and 95, and preselecting units 112b and 112c are associated with the second and third storing units of storing counter 113, and corresponding preselecting means are connected to the remaining units of the storing counter 113 so that the number of each kind of copy sheets can be selected and set in the five units 114, 115, 116, 117 and 118 of the storing counter. At the output of the storing unit 114, a potential is created which acts through gate 92 and amplifier 96 on the electromagnetic coupling 60a controlling the transporting rollers 55 of the white copy sheets 2. The outputs of the other units 115, 116, 117 and 118 will not immediately produce a potential, but will be active only when four impulses have been given by the first unit 114 which is counted back from four to zero when giving four successive impulses to gate 92.

When the start switch 90a is shortly actuated, electromagnetic coupling 60a is energized, and transporting rollers 55 transport a white copy sheet 2 to the conveyor means 70 which transport the copy sheet to the feeding means so that photoelectric sensing means 82 start the rotation of the printing roller through electromagnetic means 100. During each revolution of the printing roller, switch 102 is actuated by cam lug 101, and each impulse produced by switch 102 actuates counter 111 so that unit 114 counts back from four to one during each revolution. During the revolutions following the first revolution, switch 97 is also actuated by cam 101, and connects the respective electromagnetic coupling 60a to the voltage source.

During the fourth revolution of printing roller 3, counting unit 4 has counted back to zero so that electromagnetic means 47 is deenergized and shifts through rod 148, see FIG. 8, cam group 17, 16a, 16b to a position in which cam 17 is inoperative and can no longer produce copies of the entire printing form. The first four white copy sheets are thus imprinted by the text of the entire printing form under the control of cam 17. When during the following fifth revolution counter unit 115 is in active condition, a potential is applied to output gate 103 which connects electromagnetic coupling 60b to the voltage. When switch 97 is closed by cam 101, electromagnetic coupling 60b is energized, and yellow copy sheets are transported to the feeding means during seven consecutive revolutions of printing roller 3. The impulses from switch 102 effect the counting back in unit 115 from seven to zero so that after a printing of the seventh yellow copy sheet, no potential appears on gate 103, but the third unit 116 is activated and supplies a potential to gate 129 which is associated with the electromagnetic coupling 60c for the transporting means 57 of the red copy sheets so that five red copy sheets are imprinted with the same text, and the same operation is repeated while the units

117 and 118 are in active condition so that pink and green copy sheets are imprinted in accordance with the program.

When switches 85 and 108 are closed, but switch 104 is opened, the matrix 44 is disconnected from the electromagnetic coupling 60a to 60e of the transporting means, but remains connected to electromagnetic means 43a, 43b, 43c by which the stepwise shifting of cams 19a, 19b, 19c during successive revolutions of the printing roller are controlled. Gates 92, 103, 129, 121 and 125 are controlled by the storing counter 113, as explained above. Consequently, the copy sheets are selected and transported to the feeding means in accordance with the program stored in the storing counter 113, but after a certain number of revolutions, a different line is selected for printing by automatic turning of the cam group 19a, 19b, 19c by the stepping mechanism controlled by actuating means 43a, 43b, 43c.

The embodiment illustrated in FIGS. 11 to 15 is applied to a printing machine which corresponds to the printing machine described in detail with reference to FIGS. 5, 7 and 8 so that a detailed description of the basic construction of the machine appears unnecessary. A printing roller 3 cooperates with a counterpressure roller 13 which is controlled by cams 15, 16a, 16b associated with the head section of the printing form, a cam 17 shaped to produce an imprint of the entire printing text, and cams 19a, 19b, 19c for printing one, two or three lines of the text, and controlled by stepping mechanism to be shifted one, two or three steps under the control of actuating means 42a, 42b, 42c operated by electromagnetic means 43a, 43b and 43c. The selection of the cams is accomplished by axial shifting of the cam groups under the control of electromagnetic means 45, 46, 47, and other electromagnetic means 134, 135, 136, not shown in FIG. 11, or by direct manual operation of a rod 137, as shown in FIG. 8, but now shown in FIG. 11. As best seen in FIG. 12, the transporting conveyors and guide means are omitted in the embodiment of FIGS. 11 to 15, and a plurality of tables 50 to 54 are mounted on different horizontal levels on a support 181, each support table carrying a stack of different copy sheets 2, 4, 5, 6, 7. Transporting rollers 55 to 59 are disposed in relation to the tables 50 to 54 so as to transport the uppermost copy sheet of the respective stack, and are mounted for rotation on the walls of support 181. Each transporting roller means 55 to 59 is connected with an electromagnetic coupling 60a to 60e which are driven from a drive shaft 61 through a chain passing over chain sprockets 62 to 69 and 210.

As best seen in FIG. 15, a rack bar 203 is fixed to support 181 which is guided in guide means 206 for vertical movement with support 181 and is stopped in the lowest position by stop 209. A gear 202 meshes with rack bar 203 and is fixedly connected to a locking wheel 204 which has a cutout cooperating with a catch 205 biased by a spring 207 to engage the notch in locking wheel 204 and controlled by an electromagnetic means 185. A lug 184 is secured to support 181 and cooperates during movement of support 181 in the vertical directions of arrows H and T with control members 187 to 199 of switches 189 to 201 which are respectively controlled by relays 188 to 200. Electromagnetic means 185 is also schematically shown in the diagram on the right side of FIG. 15 and connected in parallel to an electromagnetic coupling 186 which serves to couple the drive shaft 61 with gear 202 and locking wheel 204, as best seen in FIG. 13. When gear 202 is driven, support 181 is raised, and it is possible to align each of the support tables 50 to 54 in a horizontal plane with the guide 180 so that when the corresponding transporting roller means 55 to 59 is rotated, a selected copy sheet is transported to the feeding means 48 and 49. While in the embodiment of FIGS. 5 to 10, energization of an electromagnetic coupling 60a to 60e was sufficient for the selection of a particular kind

of copy sheet, in the embodiment of FIGS. 11 to 15, support 181 must be also placed in a selected position so that the transported copy sheet is actually supplied to the feeding means.

Photoelectric sensing means 82 are again provided and are connected into a circuit corresponding to FIG. 10, electromagnetic means 100 causing actuation of a one revolution clutch by which printing roller 3 is driven by a drive motor.

Referring now to the diagram of FIG. 14, it will be seen that substantial parts of the circuit are identical with the circuit described in detail with reference to FIG. 9, the main difference being that output gates 92, 103, 129, 121 and 125 are not only connected through amplifiers 96, 106, 127, 119 and 123 to the electromagnetic coupling means 60a to 60e, but are also connected to the electromagnetic means 188, 191, 194, 197 and 200, which are also shown in FIG. 15. Electromagnetic means 188 to 200 control switches 189 to 201 which are connected in parallel to switches 187 to 199 controlled by cam lug 184 on support 181, cam lug 184 being shown in solid lines to control switch 187, while being shown in broken lines to illustrate other possible positions of cam lug 184. The voltage source is connected to a switch 211 which is connected in series with the above described switches 187, 189, 190, 192, 193, 195, 196, 198, 199 and 201. Also connected in series with this line, are electromagnetic means 185 which controls locking pawl 205, and electromagnetic coupling 186 which connects the drive gear 202 to continuously operating drive means of the machine. Nineteen output elements of matrix 44 are shown which are connected to the several gates 92, 103, 129, 125 in series according to the selected program of printing on different copy sheets.

As is apparent from the connections of matrix 44, the same is set to a particular program for first printing two white copy sheets, then three yellow copy sheets, then six red copy sheets, then four pink copy sheets, and finally four green copy sheets.

Furthermore, the program requires that the entire text of the printing form is copied on the white copy sheets 2, and that three yellow copy sheets 4 are imprinted with the first two lines Pr 1 and with the third line T3. Thereupon, the five copy sheets 5 are to be imprinted by the first two lines Pr 1, and by the fourth line T4. Following this, the first two lines and line T5 are to be printed, and the program may continue with the printing of lines T6, and T7 as explained with reference to FIG. 4. Key 85 is operated so that switches 86 and 89 are closed, and a circuit is established by switch 86 connecting gate 87, omitted in FIG. 14 for the sake of simplicity, and also to electromagnetic means 43a. Switch 89 completes the circuit to counter 91, and to electromagnetic means 45 controlling the position of cam 15 by which the head section is printed. Matrix 44 assumes its initial position, and the potential is created at the first output acting through gate 92 and amplifier 96 on electromagnetic means 47 which controls cam 17 to assume a position in which the entire text is printed. At the same time, electromagnetic coupling 60a is connected to the voltage but is not energized yet, since switches 97 and 98 are open.

The operation is started by manually closing switch 98 so that electromagnetic coupling 60a is energized and transporting rollers 55 start to rotate to move the uppermost white copy sheet 2 toward the feeding rollers 48, 49.

Relay 188 is also connected to the voltage by gate 92, so that switch 189 opens. At the same time, switch 187 is opened by cam lug 184 since this cam lug engages switch 187 when support 181 is in the position illustrated in FIG. 15 in which table 50 with copy sheets 2 is located at the level of the feeding means.

Since switch 187 is kept open by cam lug 184, electromagnetic coupling 186 is deenergized, and the drive gear 202 is not rotated so that support 181 remains in the illustrated position.

When a transported copy sheet 2 arrives at the feeding means, the photoelectric sensing means are energized, and an impulse is supplied through amplifier 99 to the starting electromagnetic means 100 which causes start of the first revolution of the printing roller.

Printing roller 3 with printing form 1 rotates while feeding rollers 48, 49 transport copy sheet 2 over the guide 180 and under the moistening means 76 to the gap between printing roller 3 and counterpressure roller 13 so that the entire text is printed on the copy sheet, under the control of cam 17. During this revolution of the printing roller, cam lug 101 actuates switch 102 so that counter 91 is shifted and the output element 2 of matrix 44 is energized and applies a potential to electromagnetic coupling 60a and electromagnetic relay 188, and to electromagnetic means 47, so that the same printing operation is repeated on the second copy sheet. Switch 97 is again operated by cam lug 101 to energize means 47, 60a and 188. When relay 188 is no longer energized, and switch 189 is closed, the circuit of electromagnetic means 185 is closed and the same is energized to retract the locking catch 205 from the locking wheel 204. At the same time, electromagnetic coupling means 186 is energized so that drive gear 202 is driven to raise rack bar 203 with support 181 in the direction of the arrow H until cam lug 184 opens contact 190 and interrupts the circuit of electromagnetic means 185 and of coupling 186. The deenergized electromagnetic means 185 no longer holds the locking catch 205 so that spring 207 locks locking wheel 204, and thereby gear 202, rack bar 203 and support 181 in the shifted position in which support table 51 is located at the level of the guide means 180 and of the feeding means.

A copy sheet 4 is now ready to be transported, relay 191 is energized by gate 103 when matrix 44 has been shifted to render output element 3 active, and contact 192 is opened. The circuit of electromagnetic means 185 and of coupling 106 is interrupted.

When switches 97 and 102 are operated by cam lug 101, electromagnetic coupling 60b is energized and transports a copy sheet 4 to the feeding means.

When a copy sheet 4 arrives at the feeding means, the photoelectric sensing means 82 cause the start of the next revolution of the printing roller 3. During the following revolutions, two prints are made on yellow copy sheets 4. During each revolution, counter 91 is actuated, and when the eighth output element of matrix 44 is rendered active, a potential appears at gate 87 which energizes electromagnetic means 43a, as described with reference to FIG. 9 so that the cam 19a is shifted by the stepping mechanism and the next following line is selected for printing during the following revolution of the printing roller. The closed switch 192 causes energization of electromagnetic means 185 and of electromagnetic coupling means 186 so that support 181 is raised. At the ninth output element of matrix 44, a gate 87 effects the shifting of cam 19a so that line 4 is printed. When all lines of the printing form are successively printed during successive revolutions of the printing roller, no copy sheet is supplied to the photoelectric sensing means 82, and the printing roller stops in its initial position. Key 211 is depressed so that its switch interrupts the circuit of switches 187, 190, 193, 196, 199, and of relays 188, 191, 194, 197 and 200. Support 181 drops until stopped by stop 209 in the initial position, and a new printing form may be placed on printing roller 3.

It will be seen that the printing operation corresponds substantially to the printing operation described with reference to FIG. 9, the difference being that energization of any gate 92, 103, 121, 125 will also cause energization of a relay having a relay switch connected in series with electromagnetic coupling means 186 which causes shifting of the support 181 to a selected position corresponding to the selection of a certain kind of copy sheet by energization of the respective correlated electromagnetic coupling 60a to 60e. Electromagnetic means 185 is con-

trolled at the same time to achieve the locking of support 181 in the selected position.

If a certain number of lines is to be printed on different kinds of copy sheets, without selection of specific lines for printing during successive revolutions of the printing roller, switch 108 is closed instead of switch 85, and key 93 of the preselection device 112a is operated to set the storing counter 113 to a preselected program, for example four white copy sheets, seven yellow copy sheets, five pink copy sheets, three red copy sheets and four green copy sheets.

A potential is created at the output of the first unit 114 of the storing counter 113 which acts through gate 92 to connect electromagnetic means 47, electric coupling means 60a, and relay 188 to the voltage. However, electromagnetic coupling 60a is not yet energized since switches 97 and 98 are open. Upon operation of switch 89, the first four copy sheets 2 are printed during successive revolutions of the printing roller, with cam operated switch 97 performing the function of the manually operated switch 98 during successive revolutions.

Counter 111 counts back and when the four copy sheets are printed, the second unit 115 of the storing counter 113 is rendered active, and gate 103 is supplied with a potential. During the first four revolutions of the printing roller, however, four white copy sheets 2 are supplied to moistening means 76 and feeding rollers 48, 49, and the printing roller 3 is started by photoelectric sensing means 82 which controls the starting magnet 100.

Switch 102 is operated by cam lug 101 to act on counter 111 to count back in the first unit 114, and when the same arrives in a position storing zero, electromagnetic means 47, which causes printing of the entire text by the corresponding cam 17, and transporting coupling 60a are de-energized. The potential is now created at the output of the second unit 115 and acts on gate 103 and amplifier 106 to energize transporting coupling 60b. Yellow copy sheets 4 are transported to the feeding means while electromagnetic coupling 186 causes movement of support 181 to the position in which the yellow copy sheets are at the level of the feeding means. Cam lug 184 opens switch 190 when support 181 assumes its correct position, so that electromagnetic means 185 is de-energized, and locking catch 205 locks wheel 204 and support 181.

The repeated closing of switch 102 during successive revolutions effects through counter 111 the counting back in the second unit 115 until seven revolutions have been completed so that during the following revolution of printing roller 3, a potential is created at the output of the third unit 116 which is connected to gate 129 associated with the red copy sheets. Transporting coupling 60c is connected to voltage, as well as relay 194 which operates switch 195. As described above, in accordance with the number of copy sheets in each series, as set in accordance with the program in the storing counter 113, gates 121, 125 are rendered active so that transporting couplings 60d and 60e are energized. As explained above, five preselecting devices, of which only three devices 112a, 112b, 112c are shown, are provided for setting the storing counter 113 to a selected program.

If switches 85 and 103 are closed, and switch 104 opened, the output gates of the matrix 44 are disconnected from gates 92, 103, 129, 125, so that the actuation of coupling 60a to 60e is carried out under the control of the storing counter 113 in accordance with the preset program, while the automatic shifting of the cams is achieved by gate 87, as explained in detail with reference to FIG. 9.

It will be understood that each of the elements described above, or two or more together, may also find a useful application in other types of printing machines differing from the types described above.

While the invention has been illustrated and described as embodied in an apparatus for selecting in accordance

with a program different kinds of copy sheets for being printed during successive revolutions of a printing roller, it is not intended to be limited to the details shown, since various modifications and structural changes may be made without departing in any way from the spirit of the present invention.

Without further analysis, the foregoing will so fully reveal the gist of the present invention that others can by applying current knowledge readily adapt it for various applications without omitting features that, from the standpoint of prior art, fairly constitute essential characteristics of the generic or specific aspects of this invention and, therefore, such adaptations should and are intended to be comprehended within the meaning and range of equivalence of the following claims.

What is claimed as new and desired to be secured by Letters Patent is:

1. A printing machine for printing on different kinds of copy sheets, comprising, in combination, printing means for printing a text comprising text sections; control means for operating said printing means to print selected text sections; feeding means for feeding different kinds of copy sheets to said printing means; programming means having a plurality of elements for representing a selected sequence of different kinds of copy sheets, said programming means being operatively connected with said control means for effecting the printing of selected text sections in accordance with a program stored in said programming means; and a plurality of selection means respectively correlated with the different kinds of copy sheets and being controlled by said programming means to cause feeding of different copy sheets by said feeding means in the sequence stored by said programming means.

2. A printing machine for printing on different kinds of copy sheets, comprising, in combination, printing means including a rotary printing roller having means for holding a printing form; feeding means for feeding different kinds of copy sheets to said printing means so that a copy sheet is printed by said printing form during each revolution of said printing roller; programming means having a plurality of consecutive series of elements having inactive and active conditions, each series including at least one element, the elements of each series representing in accordance with a program copy sheets of the same kind, and at least some of said series representing

45 in accordance with the program different kinds of copy sheets; means actuated by said printing roller during each revolution to place said elements of said programming means successively in said active condition; and a plurality of selection means respectively correlated with said

50 different kinds of copy sheets, each selection means including at least one signal lamp, different lamps having different colors respectively associated with different kinds of copy sheets, each signal lamp having an inoperative condition, and a lighted operative condition for indicating

55 by its color the kind of copy sheet to be supplied by an operating person to said feeding means for causing feeding of the supplied copy sheet by said feeding means, each signal lamp being controlled by a series of said elements representing copy sheets of the corresponding kind so that the respective signal lamp assumes said lighted condition when the elements of the controlling series assume said active condition.

3. A printing machine for printing on different kinds of copy sheets, comprising, in combination, printing means including a rotary printing roller having means for holding a printing form; control means for operating said printing means to print selected sections of the printing form; feeding means for feeding different kinds of copy sheets to said printing means so that a copy sheet is printed by said printing form during each revolution of said printing roller; programming means having a plurality of consecutive series of elements having inactive and active conditions, each series including at least one element, the elements of each series representing in

accordance with a program copy sheets of the same kind, and at least some of said series representing in accordance with the program different kinds of copy sheets, said programming means being operatively connected with said control means for effecting the printing of selected sections of the printing form in accordance with a program stored in said programming means; means actuated by said printing roller during each revolution to place said elements of said programming means successively in said active condition; and a plurality of selection means respectively correlated with said different kinds of copy sheets, each selection means including transporting means for supplying copy sheets of the respective kind to said feeding means, and having an inoperative condition and a transporting condition for transporting a copy sheet to said feeding means for causing feeding of the respective copy sheet, each transporting means being controlled by a series of said elements representing copy sheets of the corresponding kind to assume said transporting condition when the elements of the controlling series assume said active condition.

4. A printing machine for printing on different kinds of copy sheets, comprising, in combination, printing means including a rotary printing roller having means for holding a printing form; control means for operating said printing means to print selected sections of the printing form; feeding means for feeding different kinds of copy sheets to said printing means so that a copy sheet is printed by said printing form during each revolution of said printing roller; programming means including elements having inactive and active conditions, means for setting said programming means to a selected program representing a sequence of copy sheets so that a plurality of consecutive series of said elements represent copy sheets of the same kind, and so that at least some of said series represent different kinds of copy sheets, each series including at least one element, said programming means being operatively connected with said control means for effecting the printing of selected sections of the printing form in accordance with a program stored in said programming means; means actuated by said printing roller during each revolution to place said elements of said programming means successively in said active condition; and a plurality of selection means respectively correlated with said different kinds of copy sheets, each selection means having an inoperative condition, and an operative condition for causing feeding of a copy sheet of the corresponding kind by said feeding means, and being controlled by a series of said elements representing copy sheets of the corresponding kind to assume said operative condition when the elements of the controlling series assume said active condition.

5. A printing machine for printing on different kinds of copy sheets, comprising, in combination, printing means including a rotary printing roller having means for holding a printing form; feeding means for feeding different kinds of copy sheets to said printing means so that a copy sheet is printed by said printing form during each revolution of said printing roller; programming means including elements having inactive and active conditions; means for setting said programming means to a selected program representing a sequence of copy sheets so that a plurality of consecutive series of said elements represent copy sheets of the same kind, and so that at least some of said series represent different kinds of copy sheets, each series including at least one element; means actuated by said printing roller during each revolution to place said elements of said programming means successively in said active condition; and a plurality of selection means respectively correlated with said different kinds of copy sheets, each selection means including at least one signal lamp, different lamps having different colors respectively associated with different kinds of copy sheets, each signal lamp having an inoperative condition, and a lighted operative condition for indicating by its color the kind of copy sheet

to be supplied by an operating person to said feeding means for causing feeding of the supplied copy sheet by said feeding means, each signal lamp being controlled by a series of said elements representing copy sheets of the corresponding kind so that the respective signal lamp assumes said lighted condition when the elements of the controlling series assume said active condition.

6. A printing machine for printing on different kinds of copy sheets, comprising, in combination, printing means including a rotary printing roller having means for holding a printing form; feeding means for feeding different kinds of copy sheets to said printing means so that a copy sheet is printed by said printing form during each revolution of said printing roller; programming means including elements having inactive and active conditions, said programming means including electric storing means having a plurality of output gates; means for setting said programming means to a selected program representing a sequence of copy sheets so that a plurality of consecutive series of said elements represent copy sheets of the same kind, and so that at least some of said series represent different kinds of copy sheets, each series including at least one element; counting means actuated by said printing roller during each revolution to place said elements of said programming means successively in said active condition; and a plurality of selection means respectively correlated with said different kinds of copy sheets, each selection means including transporting means for supplying copy sheets of the respective kind to said feeding means, and having an inoperative condition and a transporting condition for transporting a copy sheet to said feeding means for causing feeding of the respective copy sheet, each transporting means includes at least one transporting roller adapted to transport a copy sheet, and an electromagnetic coupling having an energized condition for driving the respective transporting roller, said output gates being respectively connected with said electromagnetic couplings for causing the same to assume said energized condition, each transporting means being controlled by a series of said elements representing copy sheets of the corresponding kind to assume said transporting condition when the elements of the controlling series assume said active condition.

7. A printing machine for printing on different kinds of copy sheets, comprising, in combination, printing means including a rotary printing roller having means for holding a printing form; feeding means for feeding different kinds of copy sheets to said printing means so that a copy sheet is printed by said printing form during each revolution of said printing roller; programming means including elements having inactive and active conditions; means for setting said programming means to a selected program representing a sequence of copy sheets so that a plurality of consecutive series of said elements represent copy sheets of the same kind, and so that at least some of said series represent different kinds of copy sheets, each series including at least one element; counting means actuated by said printing roller during each revolution to place said elements of said programming means successively in said active condition; and a plurality of selection means respectively correlated with said different kinds of copy sheets, each selection means including transporting means for supplying copy sheets of the respective kind to said feeding means, and having an inoperative condition and a transporting condition for transporting a copy sheet to said feeding means for causing feeding of the respective copy sheet, said transporting means being located at different horizontal levels, each transporting means being controlled by a series of said elements representing copy sheets of the corresponding kind to assume said transporting condition when the elements of the controlling series assume said active condition, each of said selection means including a fan-shaped guide means for guiding copy sheets from the respective transporting means to said feeding means, said guide means having a

series of ends located at said levels, and a series of other ends adjacent each other and located in the region of said feeding means.

8. A printing machine for printing on different kinds of copy sheets, comprising, in combination, printing means including a rotary printing roller having means for holding a printing form; feeding means for feeding different kinds of copy sheets to said printing means so that a copy sheet is printed by said printing form during each revolution of said printing roller; programming means including elements having inactive and active conditions; means for setting said programming means to a selected program representing a sequence of copy sheets so that a plurality of consecutive series of said elements represent copy sheets of the same kind, and so that at least some of said series represent different kinds of copy sheets, each series including at least one element; counting means actuated by said printing roller during each revolution to place said elements of said programming means successively in said active condition; a plurality of selection means respectively correlated with said different kinds of copy sheets, each selection means including transporting means for supplying copy sheets of the respective kind to said feeding means, and having an inoperative condition and a transporting condition for transporting a copy sheet to said feeding means for causing feeding of the respective copy sheet, each transporting means being controlled by a series of said elements representing copy sheets of the corresponding kind to assume said transporting condition when the elements of the controlling series assume said active condition; a support for supporting said transporting means spaced from each other in substantially vertical direction; and shifting means for shifting said support in said direction between a plurality of positions for placing each of said transporting means at the level of said feeding means, said shifting means being controlled and operated by said programming means so that a series of elements in said active condition causes movement of said support by this shifting means to a position in which the transporting means correlated with the same kind of copy sheets as said last-mentioned series are located at said level of said feeding means.

9. A printing machine for printing on different kinds of copy sheets, comprising, in combination, printing means for printing a text comprising text sections; control means for operating said printing means to print selected text sections; feeding means for feeding different kinds of copy sheets to said printing means; programming means having a plurality of elements for representing a selected sequence of different kinds of copy sheets, said programming means being operatively connected with said control means for effecting the printing of selected text sections in accordance with a program stored in said programming means; and a plurality of selection means respectively correlated with the different kinds of copy sheets, each selection means including transporting means for transporting copy sheets of the respective kind to said feeding means, said transporting means being controlled by said programming means to supply copy sheets in said sequence to said feeding means to cause feeding of copy sheets by said feeding means in the sequence stored by said programming means.

10. A printing machine for printing on different kinds of copy sheets, comprising, in combination, printing means including a rotary printing roller having means for holding a printing form; control means for operating said printing means to print selected sections of the printing form; feeding means for feeding different kinds of copy sheets to said printing means so that a copy sheet is printed by said printing form during each revolution of said printing roller; programming means having a plurality of consecutive series of elements having inactive and active conditions, each series including at least one element, the elements of each series representing in accordance with a program copy sheets of the same kind,

and at least some of said series representing in accordance with the program different kinds of copy sheets, said programming means being operatively connected with said control means for effecting the printing of selected sections of the printing form in accordance with a program stored in said programming means; means actuated by said printing roller during each revolution to place said elements of said programming means successively in said active condition; and a plurality of selection means respectively correlated with said different kinds of copy sheets, each selection means having an inoperative condition, and an operative condition for causing feeding of a copy sheet of the corresponding kind by said feeding means, and being controlled by a series of said elements representing copy sheets of the corresponding kind to assume said operative condition when the elements of the controlling series assume said active condition.

11. A printing machine for printing on different kinds of copy sheets, comprising, in combination, printing means including a rotary printing roller having means for holding a printing form; control means for operating said printing means to print selected sections of the printing form; feeding means for feeding different kinds of copy sheets to said printing means so that a copy sheet is printed by said printing form during each revolution of said printing roller; programming means including elements having inactive and active conditions; means for setting said programming means to a selected program representing a sequence of copy sheets so that a plurality of consecutive series of said elements represent copy sheets of the same kind, and so that at least some of said series represent different kinds of copy sheets, each series including at least one element, said programming means being operatively connected with said control means for effecting the printing of selected sections of the printing form in accordance with a program stored in said programming means; counting means actuated by said printing roller during each revolution to place said elements of said programming means successively in said active condition; and a plurality of selection means respectively correlated with said different kinds of copy sheets, each selection means including transporting means for supplying copy sheets of the respective kind to said feeding means, and having an inoperative condition and a transporting condition for transporting a copy sheet to said feeding means for causing feeding of the respective copy sheet, each transporting means being controlled by a series of said elements representing copy sheets of the corresponding kind to assume said transporting condition when the elements of the controlling series assume said active condition.

12. A printing machine for printing on different kinds of copy sheets, comprising, in combination, printing means including a rotary printing roller having means for holding a printing form; control means for operating said printing means to print selected sections of the printing form; feeding means for feeding different kinds of copy sheets to said printing means so that a copy sheet is printed by said printing form during each revolution of said printing roller; programming means including elements having inactive and active conditions; means for setting said programming means to a selected program representing a sequence of copy sheets so that a plurality of consecutive series of said elements represent copy sheets of the same kind, and so that at least some of said series represent different kinds of copy sheets, each series including at least one element, said programming means being operatively connected with said control means for effecting the printing of selected sections of the printing form in accordance with a program stored in said programming means; counting means actuated by said printing roller during each revolution to place said elements of said programming means successively in said active condition; a plurality of selection means respectively correlated with said different kinds of copy sheets, each se-

lection means including transporting means for supplying copy sheets of the respective kind to said feeding means, and having an inoperative condition and a transporting condition for transporting a copy sheet to said feeding means for causing feeding of the respective copy sheet, each transporting means being controlled by a series of said elements representing copy sheets of the corresponding kind to assume said transporting condition when the elements of the controlling series assume said active condition; and photoelectric sensing means located intermediate said transporting means and said feeding means for sensing copy sheets and operatively connected with said printing roller for starting a revolution of the same when sensing a copy sheet.

13. A printing machine for printing on different kinds of copy sheets, comprising, in combination, printing means including a rotary printing roller having means for holding a printing form; feeding means for feeding different kinds of copy sheets to said printing means so that a copy sheet is printed by said printing form during each revolution of said printing roller; programming means including a plurality of contacts, and a plurality of consecutive series of connector elements connected to said contacts in accordance with a program, the elements of each series representing copy sheets of the same kind, and at least some of said series of connector elements representing different kinds of copy sheets, each series of connector elements including at least one connector element; a rotary contact arm driven in synchronism with said printing roller to successively engage said contacts to place said connector elements successively in an energized condition; and a plurality of series of signal lamps of the same color, different series having lamps of different colors respectively associated with different kinds of copy sheets, said series of signal lamps being respectively connected to corresponding series of connector elements, each signal lamp assuming a lighted condition when the corresponding contact and connector element is energized by said contact arm, the color of each lighted lamp indicating the kind of copy sheet to be supplied by an operating person to said feeding means for causing feeding of the supplied copy sheet by said feeding means.

14. A printing machine as set forth in claim 11, wherein said programming means includes a matrix having a plurality of output elements, and a plurality of output gates, a series of said output elements being connected to each of said output gates in accordance with a program; each of said output gates being connected to one of said transporting means for placing the same in said transporting condition, and another output gate connected to output elements of said matrix, selected in accordance with another program, and operatively connected with said control means so that the same operate said printing means to print selected sections of the printing form in accordance with said last-mentioned program on different kinds of copy sheets selected in accordance with said first-mentioned program.

15. A printing machine as set forth in claim 14, wherein said control means include a stepping mechanism, and actuating means for operating said stepping mechanism after each revolution of said printing roller, said actuating means being operatively connected with said other output gate and controlled by the same.

16. A printing machine as set forth in claim 14, wherein said printing means are movable to and from a printing position, and include a cam follower means for moving the same to said printing position; and wherein said control means include cam means cooperating with said cam follower for placing said printing means in said printing position when selected sections of the printing form are positioned to be printed, and electromagnetic means for controlling the position of said cam means, and connected to said other output gate so that said cam means are set in accordance with said other program.

17. A printing machine as set forth in claim 11, wherein in said programming means include two electric storing means, and wherein said counter means include two counter means respectively connected with said two storing means, one of said storing means being connected with said control means for causing printing of selected sections of the printing form in accordance with a program, and at least the other storing means having outputs connected with said transporting means for controlling the same.

18. A printing machine as set forth in claim 7, wherein in said guide means include a plurality of conveyors having a series of ends located at the levels of said transporting means, and other ends closer spaced than said last-mentioned ends, and a plurality of guides having one series of ends located opposite said other ends of said conveyor means and other ends located adjacent each other in the region of said feeding means.

19. A printing machine as set forth in claim 8, wherein in said programming means include an electric storing means having a plurality of series of output line elements, and a plurality of output gates connected to the line elements of each series, respectively, each output gate being operatively connected with said shifting means for causing placing of the transporting means correlated with the respective series on the level of said feeding means.

20. A printing machine as set forth in claim 19, wherein in said shifting means include a rotary shifting member for moving said support, and an electromagnetic coupling having an energized condition for connecting said rotary shifting member with a drive means; and wherein an impulse through the respective output gate causes said coupling to assume said energized condition.

21. A printing machine as set forth in claim 19, wherein in said printing means include control means for operating said printing means to print selected sections of the printing form, said control means being connected to at least one output gate of said electric storing means and operated in accordance with a program stored in said storing means.

22. A printing machine as set forth in claim 7, wherein the distance between each of said transporting means and said feeding means is substantially the same.

23. A printing machine for printing on different kinds of copy sheets, comprising, in combination, printing means including a rotary printing roller having means for holding a printing form for printing a text comprising text sections; control means for operating said printing means to print selected text sections; feeding means for feeding different kinds of copy sheets to said printing means so that a copy sheet is printed by said printing form during each revolution of said printing roller; programming means including elements having inactive and active conditions, said programming means including at least one storing counter means having a plurality of storing units respectively adapted to store a series of counting elements so that each unit can be set in accordance with a program to the number of counting elements of the respective series; means for setting said programming means to a selected program representing a sequence of selected text sections to be printed and a corresponding sequence of copy sheets so that a plurality of consecutive series of said elements represent copy sheets of the same kind, and so that at least some of said series represent different kinds of copy sheets, each series including at least one element; counting means actuated by said printing roller during each revolution to place said elements of said programming means successively in said active condition; connecting means connecting said programming means with said control means for effecting the printing of selected text sections in accordance with the setting of said programming means; and a plurality of selection means respectively correlated

with said different kinds of copy sheets, each selection means including transporting means for supplying copy sheets of the respective kind to said feeding means, and having an inoperative condition and a transporting condition for transporting a copy sheet to said feeding means for causing feeding of the respective copy sheet, each transporting means being controlled by a series of said elements representing copy sheets of the corresponding kind to assume said transporting condition when the elements of the controlling series assume said active condition.

24. A printing machine for printing on different kinds of copy sheets, comprising, in combination, printing means including a rotary printing roller having means for holding a printing form; feeding means for feeding different kinds of copy sheets to said printing means so that a copy sheet is printed by said printing form during each revolution of said printing roller; programming means including elements having inactive and active conditions, said programming means including at least one storing counter means having a plurality of storing units respectively adapted to store a series of counting elements so that each unit can be set in accordance with a program to the number of counting elements of the respective series; means for setting said programming means to a selected program representing a sequence of copy sheets so that a plurality of consecutive series of said elements represent copy sheets of the same kind, and so that at least some of said series represent different kinds of copy sheets, each series including at least one element; counting means actuated by said printing roller during each revolution to place said elements of said programming means successively in said active condition, said counting means being connected with said storing counter means to successively place each unit in an active condition while counting back each unit; and a plurality of selection means respectively correlated with said different kinds of copy sheets, each selection means including transporting means for supplying copy sheets of the respective kind to said feeding means, and having an inoperative condition and a transporting condition for transporting a copy sheet to said feeding means for causing feeding of the respective copy sheet, each of said units having an output, said outputs being respectively connected to said transporting means for placing the same in said transporting condition while the respective unit is in said active condition cooperating with said counter means, each transporting means being controlled by a series of said ele-

ments representing copy sheets of the corresponding kind to assume said transporting condition when the elements of the controlling series assume said active condition.

25. A printing machine for printing on different kinds of copy sheets, comprising, in combination, printing means including a rotary printing roller having means for holding a printing form; feeding means for feeding different kinds of copy sheets to said printing means so that a copy sheet is printed by said printing form during each revolution of said printing roller; programming means including elements having inactive and active conditions, said programming means including a matrix having a plurality of output elements, and a plurality of output gates, a series of said output elements being connected to each of said output gates in accordance with a program; means for setting said programming means to a selected program representing a sequence of copy sheets so that a plurality of consecutive series of said elements represent copy sheets of the same kind, and so that at least some of said series represent different kinds of copy sheets, each series including at least one element; counting means actuated by said printing roller during each revolution to place said elements of said programming means successively in said active condition; and a plurality of selection means respectively correlated with said different kinds of copy sheets, each selection means including transporting means for supplying copy sheets of the respective kind to said feeding means, and having an inoperative condition and a transporting condition for transporting a copy sheet to said feeding means for causing feeding of the respective copy sheet, each of said output gates being connected to one of said transporting means for placing the same in said transporting condition, each transporting means being controlled by a series of said elements representing copy sheets of the corresponding kind to assume said transporting condition when the elements of the controlling series assume said active condition.
